UNITED STATES PATENT OFFICE.

FRIEDRICH ILSEMANN, OF HORN, NEAR BREMEN, GERMANY, ASSIGNOR TO THE FIRM OF METALL-INDUSTRIE UND HANDELS-GESELLSCHAFT MIT BESCHRANKTER HAF-TUNG, OF BREMEN, GERMANY.

DEVICE FOR LIFTING VEHICLES, PARTICULARLY MOTOR-CARS.

1,150,599.

Specification of Letters Patent.

Patented Aug. 17, 1915.

Application filed January 2, 1914. Serial No. 810,070.

To all whom it may concern:

Be it known that I, FRIEDRICH ILSEMANN, a subject of the King of Prussia, German Emperor, residing at Horn, near Bremen, in the Kingdom of Prussia, German Empire, have invented certain new and useful Improvements in Devices for Lifting Vehicles, Particularly Motor-Cars, of which the following is a specification.

10 This invention relates to a device for lifting and supporting vehicles, particularly motor cars which is constructed in such a manner that the bearing surface which acts at the beginning of the lifting of the vehicle has a shorter radial distance from the point around which the lever pivots than the bearing surfaces on which the vehicle rests when it has been completely lifted.

20 In the accompanying drawings the invention is shown by way of example:—

Figure 1 is a side elevation of a motor car with the lifting levers. Fig. 2 shows on a larger scale an axle and part of a wheel with the lifting device. Fig. 3 is a part plan view 25 of Fig. 2. Fig. 4 shows in side elevation another construction of the lifting lever.

According to the invention levers *c* are pivotally arranged near the wheel axles *b*. The levers *c* are adapted to be lowered and lifted. In order to obtain the lifting of the vehicle when said levers *c* are pressed upon the ground, said levers are angular and they are longer than the distance between the pivot pins *d* of said levers and the ground. 35 In the lower ends of the levers *c* rollers *e* are mounted. The levers are arranged in such a manner that they are lowered in a direction opposite to the direction in which the vehicle runs so that when the vehicle 40 moves back it is automatically lifted by means of the lifting levers which have been previously lowered. The bearing surface *m* of the lifting lever which acts at the beginning of the lifting of the vehicle is arranged 45 so that its radial distance from the axis of the pivot pin is shorter than the distance at which the bearing surface *e* is situated on which the vehicle rests when it is completely lifted. The lifting levers can be fork-shaped 50 as shown in Fig. 3 and they are influenced by a spring *f* wound around the pivot pin *d*. The lever *c* has at its upper end a forwardly projecting arm *g* to which a pull rope *h* is

attached which can be pulled by the driver in order to lower the lever *c* against the 55 action of the spring *f*. The lever *c* has further a forwardly projecting spur *n* designed to pull the lever gradually into the lifting position when the car runs back so that the car has sufficient energy to get into 60 and to remain in the lifted position when the driving wheels are lifted off the ground. The spur *n* is preferably hingedly connected with the lever *c* so that it can be laid against said lever and secured in this position by 65 means of the nipple *o* adapted to engage with the corresponding notch of the spur.

According to Fig. 4 the lifting lever is composed of two levers *c* and *i* which are independent the one from the other and coupled 70 together so that they have sufficient play. With this object in view the lever *i* has an arm *k* which carries a catch projecting on the path of the lever *c* so that if said lever *c* is lowered the lever *i* is drawn along and 75 adopts a position which forms an angular position with regard to the lever *c* (Fig. 4). If the vehicle is lifted the lever *i* bears on the ground and eases the lever *c*.

I claim:—

1. An improved lifting jack for motor cars comprising in combination a lever pivotally mounted on the car frame under the wheel axle, said lever having two bearing points one of which is arranged at a shorter 85 radial distance from the pivot of said lever than the other which serves for supporting the lifted car, a spring influenced spur hinged on said lever at said bearing point which has a shorter radial distance from the 90 pivot than the supporting point, for the purpose of gradually lifting the car when the lifting jack is lowered, so that said car is first slightly lifted by said spur before it comes to rest on the bearing point proper, 95 substantially as described and shown and for the purpose set forth.

2. An improved lifting jack for motor cars comprising in combination a lifting lever, a pivot pin for pivotally mounting 100 said lifting lever under the frame of the car below the wheel axle, said lifting lever having two bearing points one of which is situated at a shorter distance from said pivot pin than the other, a spring influenced spur 105 hinged to said lifting lever at the bearing

point situated at a shorter distance from said pivot than the other bearing point, and a second lever loosely mounted on said pivot pin designed to release the pivot of the lifting lever when the same is in supporting position substantially as described and shown and for the purpose set forth.

In witness whereof I have hereunto set my hand in the presence of two witnesses.

FRIEDRICH ILSEMANN.
